MANIFOLDING DEVICE

William C. Pfeiffer, Dayton, Ohio, assignor to The Egry Register Company, Dayton, Ohio, a corporation of Ohio

Application May 5, 1939, Serial No. 271,979

16 Claims. (Cl. 271—2.1)

This invention relates to a manifolding machine and more particularly to such a manifolding machine which is adapted to be used as an attachment to a printing or typing machine in order to produce a multiple number of copies of the material being printed or typed. Still more particularly, the invention relates to a manifolding attachment which is provided with means for feeding the duplicate sheets embodying pins which are adapted to engage with elongated slots in an untyped or unprinted portion of the sheets, and to such a device wherein the feeding means is laterally adjustable with respect to the sheets so that the feeding slots in the sheets may be located at any desired lateral position on the sheets and so that the feeding pins may be adjusted to correspond with the location of the feeding slots in the particular sheets being printed.

In my copending application, Serial No. 259,395, filed March 2, 1939, I have disclosed a manifolding device which is of the same general type as the manifolding device of this invention and wherein the sheets are provided with spaced elongated apertures near or on the center line thereof, the feeding pins being disposed in a fixed position in the center of the machine. This arrangement is in practice found to be disadvantageous since the machine is not versatile to take care of different requirements but is useable only with sheets which are apertured at their center. It is desirable to provide these sheets with apertures at any location laterally thereof. For example, it is frequently inconvenient to have the apertures in the center of the sheet because it is desired to print in the center. In many cases, it is desirable to have the feeding apertures located in a non-used section of the sheet and this non-used section is very often located at a considerable distance from the center of the sheet. In other cases, it is desirable to have the apertures in line with a line on the sheet since it would not be customary or desirable to print on such a line. This line more frequently than not falls at a substantial distance from the center of the sheet and, therefore, the device of my co-pending application referred to above is not applicable when the apertures are so located. It will be understood that when using feeding apertures in the body of the sheet that these apertures are located in such position that they pass by an unused portion of the printing and typing machine with which the manifolding device is employed.

In order to allow the location of the feeding apertures at substantially any position laterally

of the sheet, the present invention provides for lateral adjustment of the feeding pins with respect to the manifolding device.

It is the principal object of the present invention to provide a manifolding device adapted to be attached to a printing or typing machine, and provided with means for feeding a plurality of paper webs past the printing or typing position, this feeding means being laterally adjustable with respect to the machine.

Another object is to provide a manifolding device of the foregoing type wherein the feeding means engages a single row of spaced apertures.

Another object is to provide a manifolding device of the foregoing type wherein the feeding pins engage apertures disposed at any lateral position in the body of the sheets, said apertures being located in the generally central portion of the sheets.

Still another object is to provide a device of the foregoing type wherein the feeding means is aligned with any non-used portion of the typing or printing machine. For example, typing or printing machines are commonly provided with spaced type bar guides between which the type bars engage the original sheet. These type bar guides are of substantial width and in accordance with a preferred embodiment of the present invention, the feeding apertures in the sheets are in alignment with one of these type bar guides, the feeding means being similarly aligned. In this embodiment, the feeding means is laterally adjustable to a plurality of positions, each of which coincides with these type bar guides so that the apertures may be located in the sheets at practically any desired lateral position.

Still another object is to provide a device of the foregoing type wherein the chain carrying the feeding pins is provided with means for keeping it taut which means moves laterally with the feeding device.

Referring to the accompanying drawings:

Figure 1 is a front elevation of one form of the manifolding device of this invention.

Figure 8 is a section on the line 8—8 of Figure 7, looking in the direction of the arrows.

Figure 9 is a perspective showing the driving connection between the platen gear and the feeding drive shaft.

General arrangement

In general, the manifolding device of this invention is an attachment to be attached to a main typing or printing machine, such as a tabulating machine, typewriter or adding machine. Such a machine ordinarily has its own printing mechanism, including type and an inking ribbon, together with means for printing a single copy of a record or multiple copies by using carbon paper sheets interleaved between the multiple paper sheets or webs.

The manifolding device serves to carry and feed a plurality of paper webs, each web usually consisting of a series of printed paper forms separated from one another by weakening lines or perforations. The manifolding device of the present invention employs duplicating ribbons, such as carbon paper ribbons, interleaved between the paper webs and crossing the paper webs transversely at the printing position. Mechanism for feeding the paper webs and carbon ribbons is synchronized with the operation of the main printing machine so that it operates in cooperation with the line spacing or ejection spacing movement of the platen of the main machine, and may be driven from this platen.

In the manifolding device of the present invention, the paper webs are advanced by a feeding mechanism which comprises a series of vertically disposed spaced fingers which engage correspondingly shaped apertures disposed longitudinally of the sheets. The paper webs are provided with elongated apertures, preferably rectangular, which are engaged by the feeding pins mounted at intervals along a single sprocket chain. The present machine also provides a contact structure which presses against the paper webs and maintains them in engagement with the feeding pins near the path of the webs where the feeding apertures are located. This contact structure may be moved away from the webs so as to facilitate the threading of the webs through the device.

The feeding pins and chain, the contact structure, and the stripping drums are all mounted on a laterally adjustable carriage which is provided with stops causing the feeding pins to be in alignment with the gaps in the printing mechanism occasioned by the type bar guides. Thus the mechanism is capable of lateral adjustment so that the feeding holes may be located at any lateral position on the sheets being printed.

In my co-pending application above identified, the feeding pins are disposed so as to engage the center path of the webs and are not adjustable. The present invention provides means for adjusting the feeding pins laterally, thereby overcoming the disadvantages of the machine described in said application occasioned by the non-adjustability of the feeding pins.

Main printing machine construction

The main printing machine to which the manifolding device of the present invention is at-

tached forms no part of the present invention, and may be a tabulating machine, an adding machine, a typewriter, or any other suitable machine capable of printing a record. In the accompanying drawings, a manifolding device of this invention is shown as used in conjunction with a tabulating and listing machine. The mechanism thereof is beyond the scope of the present disclosure except as its parts cooperate with the mechanism of a manifolding device, such as the paper feeding mechanism. Referring to the drawings in detail, the main printing machine 10 has type bar guides 11 engaging type bars (not shown) actuated by mechanism within the machine for printing records upon paper webs 12 by means of a fabric inking ribbon which prints the original. The machine 10 is provided with a rotatable platen 13, on which is mounted a platen gear 14 carried on the platen shaft 15. The platen gear 14 is driven by gearing (not shown) contained within the main printing machine 10 and forming no part of the present invention. By reason of this gearing, the platen 13 is rotated at suitable times after a row of type has been printed so as to bring about a line spacing operation, or after a plurality of rows of type have been printed and a paper form completely filled out, bringing about an ejection spacing operation.

It will be understood that in the present invention the gripping rolls ordinarily provided beneath the platen 13 for holding the paper firmly in engagement with the platen are released so that the paper webs slide loosely around the platen 13 and are not affected by its rotation. Instead a feeding of the paper webs is accomplished entirely by mechanism within the manifolding device itself, as will hereinafter appear.

The manifolding device of the present invention is mounted upon the tabulating machine 10, the frame of which is provided with cross rods 17 and 18 and with pivot bolts 19, upon which rest side members 20 of the manifolding device, the manifolding device being pivotally rotatable about pivot bolts 19.

The L-shaped side members 20 are so disposed that portion 21 projects rearwardly and surrounds pivot bolts 19 while portion 22 is vertically disposed and carries the apparatus of the present invention.

The several webs 12 are fed around platen 13, at which point there is interleaved between them carbon paper ribbons 23. When the type bars are manipulated into engagement with platen 13, they operate to form an original copy by means of the usual fabric ribbon (not shown) used outwardly of the web assembly, and make the carbon copies by reason of these interleaved paper ribbons 23. It will be understood that instead of using paper ribbons which are employed only a single time and are then discarded, the usual cloth ribbons employed a number of times may be utilized. These ribbons 23 are fed transversely between the paper webs 12 at the printing position. The details of the mechanism by which they are fed past the printing position form no part of the present invention and a complete disclosure thereof may be found in my copending application Serial No. 258,014 filed February 23, 1939. For purposes of the present disclosure, it will suffice to state that the ribbons 23 are fed in synchronism with the line-feeding and ejecting-feeding mechanism of the main printing machine in such manner that the ribbons are fed a predetermined amount for a

line spacing operation and a greater amount for an ejection spacing operation.

The side members 20 are maintained in the proper stationary position by rods 24, 25, and 26 which are held in engagement with members 22 by screws 27 passing through members 22 into the ends of the rods. Rods 25 and 26 engage blocks 28 disposed inwardly of members 22 and are thus more rigidly supported. Disposed between supports 22 is a rotatable shaft 29 which is driven by shaft 33a upon which is mounted miter gear 30 meshing with gear 31 mounted on shaft 29. Shaft 33a is driven by a motor (not shown) acting through a clutch actuated by the tabulating machine. Shaft 29 actuates the ribbon feed at the left hand side of the machine and the ribbon clamp at the right hand side. The ribbon feed is fully described in my application Serial No. 258,014 above-identified.

Likewise disposed laterally of the machine between supports 22 is a rotatable shaft 32 which drives the paper feeding mechanism of this invention in synchronism with the spacing operations accomplished by platen gear 14.

Shaft 32 is driven by gearing designated generally as 33 (see Figure 9) connecting it with platen gear 14 so that the paper webs 12 will be fed in accordance with the spacing provided by printing machine 10.

Slidably mounted on feeding drive shaft 32 is a feeding sprocket 34 which cooperates with sprocket 35 disposed vertically thereabove to support the feed sprocket chain 36 which passes therearound. Feed sprocket 34 is mounted upon a steel bushing 37 which is slidably keyed on shaft 32 by feather key 38 which is attached to the hub of sprocket 34 and is slidable with respect to keyway 39 in shaft 32. If desired, instead of keying, suitable splining may be employed to cause sprocket 34 to be driven by shaft 32. Alternatively, two or more feather keys may be provided to reduce the axial force required to move the sprocket along shaft 32. Bronze bushings 39a at either side of sprocket 34 slidably engage the surface of shaft 32. These bushings are carried in side frame members 40 which are parallelly disposed vertically. Frame members 40 surround each of shafts 24, 25, 26, 28 and 32. Bronze bushings 41 are provided in side members 40 for sliding engagement with shaft 28. Bronze sleeve 42 is provided within side members 40 for sliding engagement with rod 26. Bronze sleeve 43 is similarly provided for sliding engagement with rod 25. Bronze sleeve 44 is provided for sliding engagement with rod 24.

Fixedly surrounding rods 25 and 26 are additional braces 45 which at their lower ends surround rotatable shaft 29. These members 45 lend additional support to the machine and to shaft 29.

At the top of vertical members 40, there is disposed in the slots formed by ears 51 a fixed lateral tie rod 46, which passes through sprocket 35 and upon which are rotatably mounted drums 47 which guide the upfed webs 12 around to the rear of the machine and strip them from sprocket chain 36. Rod 46 is fixedly held in end frame members 48 by screws 77 and 77a. End members 48 are integral with the inclined arms of yoke member 49 located just in the rear of sprocket chain 36 (see Figures 1 and 2). Yoke 49 is connected to flat ears 50 which are integral with upstanding side members 40.

As a result of the foregoing construction, the

side frame members 40, the sprockets 34 and 35 and drums 47 with their associated supporting mechanism are all laterally slidable with respect to the machine.

5 In order to locate this slideable carriage and feeding device in a fixed position, rod 25 is provided with a series of circumferential parallel slots 51 which are located with respect to type bar guides 11 so that sprocket chain 36 will always be in alignment with and opposite a type bar guide 11. U-shaped locking members 52 are provided which are disposed in the appropriate slots 51 at the ends of bronze sleeve 43 (see Figure 7) and when it is desired to position the feeding device, locking members 52 are manually removed, the feeding carriage is slid manually to the right or to the left, as desired, to the appropriate position whereupon locking members 52 are replaced in slots 51. Thus, the operator is enabled to locate the feeding carriage properly with respect to the webs 12 being acted upon by the printing machine 10.

Sprocket 35 is provided with an internal bronze bushing 53 which is mounted in a U-shaped member 54. A spring 55 presses against a lower portion 56 of this U-shaped member 54 and against the top of bronze sleeve 44, thereby maintaining sprocket chain 36 always taut, since clearance is provided in bushing 53 around fixed tie rod 46.

In order to hold vertical feeder frame members 40 in fixed relation with respect to one another, lateral bolts 58 and spacers 59 are provided. U-shaped member 54 is provided with downwardly extending leg members 60 which surround sleeve 44 and with side members 40 form an enclosure for spring 55 and are adapted to slide up and down with respect to sleeve 44.

Sprocket chain 36 is provided with fingers 61 which are spaced at appropriate intervals to cooperate with the vertically disposed feeding slots 62 cut in webs 12. These fingers 61 comprise a horizontal portion 63 and an angular portion 64. The point 65 formed by these sides 63 and 64 is adapted to enter the rectangular apertures 62 of the webs 12 and to thereby feed the web upwardly. In Figure 2, two of these fingers 61 are shown in engagement with webs 12.

Disposed roughly parallel to the webs 12 and forwardly of the sprocket chain 36, there is provided a paper ball generally designated 66 for holding the sheets 12 in engagement with the feeding fingers 61. This ball 66 comprises a horizontal portion 68 which depends from end supports 67 by means of integral members 69. Fixedly attached to members 68 are vertical bail members 69 which comprise a straight portion 70 and an arcuate portion 71 which is substantially concentric with drums 47. Fixedly attached to the lower portions of members 68 is another horizontal bail member 71.

The bail assembly just described is rotatable vertically about shaft 46 in order to allow for threading of the paper webs 12 around sprocket chain 36 and stripping drums 47. This is accomplished by having the ball assembly pivotally supported from rod 46 by arms 67. Fixedly attached to one end of bail member 69 is an auxiliary member 72 which is generally circular in configuration and which pivotally engages rod 46. This member 72 is provided with peripheral notches 73 and 74. A detent 75 is urged into engagement with notches 73 and 74 by a spring 76 which is attached to rod 46 by screw 77a and has its other end encircling detent 75. Detent

75 is mounted on a pivoted arm 78 which is pivoted to side frame 48 at 79. Detent 75 can be pulled out of engagement with the notches in member 72 manually, whereupon the ball assembly 80 may be swung upwardly or downwardly about the center of rod 46. When pin 76 engages notch 74, the ball assembly 80 is in the operating position shown in Figures 1, 2, and 5. When pin 76 is in engagement with notch 73, the ball assembly 80 is locked in a position for threading of webs 12 and through the machine.

An adjusting screw 75a is threaded within a fixed stud 75b mounted on pivoted arm 78 and engages an outwardly turned ear 75c on circular member 72, thereby providing an adjustable stop to limit the downward movement of ball 80 towards the sheets 12. This screw 75a is normally so adjusted that detent 75 engages the upper portion of notch 74.

As will be understood as webs 12 are fed upwardly by fingers 61 around drums 47, they are stripped from the feeding fingers 61 by drums 47 and thence pass into a tray or other receptacle provided at the proper position at the rear of the machine.

The mode of operation of the machine will be obvious from the foregoing description. For the sake of completeness, however, it is pointed out that ball assembly 80 will first be swung upwardly out of operative position into the threading position and the webs 12 will be threaded in engagement with feeding pins 61 and drums 47 whereupon ball assembly 80 will be lowered to the operative position and the machine is ready for operation. Ready adjustment of the feeding carriage laterally of the machine is obtained by means of locking members 82 and slots 81. As previously explained, slots 81 are disposed apart from each other at the same distances as the type bar guides 11 so that the apertures 82 in the sheets 12 may be located at a point where normally no printing would occur.

Figures 3 and 4 illustrate the versatility of the machine of the present invention. In Figure 3, there is portrayed a sheet 12 which has the rectangular slots 62 disposed well from the center thereof and in alignment with a vertical line of the sheet. This location of the holes 62 interferes with the utility of the blank 12 to the least possible extent. In Figure 4 there is shown a web 12 wherein the perforations 62 are disposed well on the other side of the center of the web. In this instance, perforations 62 are located in a narrow column especially provided for the purpose.

It will be understood that the lateral adjustment of the feeding device of the present invention makes possible the location of the feeding apertures 62 in practically any position desired and thus greatly increases the versatility of the manifolding machine. In this way, the location of the feeding apertures may be varied to suit the particular blanks at hand. These advantages are obtained without sacrificing any of the advantages of the machines set forth in my co-pending applications identified herein.

It is to be understood that I intend to comprehend as within my invention such modifications as may be necessary to adapt it to varying conditions and uses.

Having thus fully described my invention, what I claim as new and desire to secure by Letters Patent, is:

1. In a manifolding machine adapted to be employed in association with a record printing

machine, means for feeding a plurality of superimposed sheets comprising a feeding finger adapted to engage a cooperating aperture in the sheets being fed and to move said sheets therewith, said feeding means being adjustable laterally with respect to said sheets in a plurality of predetermined laterally spaced positions of lateral adjustment, spacer means determining said predetermined positions, and means cooperating with said spacer means for locking said feeding means in any of said positions of adjustment.

2. In a manifolding machine adapted to be employed in association with a record printing machine, means for feeding a plurality of superimposed sheets comprising a feeding finger adapted to engage a cooperating aperture in the sheets being fed and to move said sheets therewith, and means adapted to allow adjustment of the lateral position of said feeding means with respect to said sheets comprising laterally stationary means having a plurality of locking means formed thereon and laterally spaced thereon and upon which said feeding means is laterally slidably, and means selectively engageable with and disengageable from said locking means for locking said feeding means to or unlocking it from any one of said locking means.

3. In a manifolding machine adapted to be employed in association with a record printing machine having laterally spaced type bar guides, means for feeding a plurality of superimposed sheets comprising a feeding finger adapted to engage a cooperating aperture in the sheets being fed and to move said sheets therewith, said feeding finger being laterally adjustable with respect to said sheets and being lockable in a plurality of predetermined laterally spaced positions of lateral adjustment, and means allowing locking of said feeding finger laterally only when said feeding finger is in alignment with said type bar guides.

4. In a manifolding machine adapted to be employed in association with a record printing machine having laterally spaced type bar guides, means for feeding a plurality of superimposed sheets comprising a feeding finger adapted to engage a cooperating aperture in the sheets being fed and to move said sheets therewith, and having means for allowing adjustment of the lateral position of said feeding means with respect to said sheets comprising a stationary rod non-rotatably fixed in the frame of the manifolding machine and having a plurality of independent annular locking recesses laterally spaced thereon in such position with respect to said type bar guides that when said feeding means is locked to one of said recesses said feeding finger is in alignment with one of said type bar guides, said feeding means being laterally slidable on said rod and having means for locking said feeding means to any one of said locking recesses.

5. In a manifolding machine, a supporting frame, means supported thereby for feeding a plurality of superimposed sheets and comprising a feeding finger adapted to engage a cooperating aperture in a plurality of superimposed sheets being fed, means laterally stationary with respect to said frame and with respect to which said feeding means is laterally slidable, a plurality of laterally spaced means on said stationary means, and means adapted selectively to engage and disengage said spaced means for locking said feeding means to or unlocking it from any one of said laterally spaced means.

6. In a manifolding machine, a supporting

frame, means supported thereby for feeding a plurality of superimposed sheets and comprising a feeding finger adapted to engage a cooperating aperture in a plurality of superimposed sheets being fed, stationary means non-rotatably fixed to said frame and with respect to which said feeding means is laterally slidable, a plurality of independent laterally spaced projections on said stationary means, a sleeve fixedly secured to said feeding means and surrounding said stationary means, and means associated with said sleeve engaging said projections for preventing any lateral adjustment of said sleeve and thereby said feeding means.

7. In a manifolding machine, a supporting frame, means supported thereby for feeding a plurality of superimposed sheets and comprising a finger adapted to engage a cooperating aperture in a plurality of superimposed sheets being fed, means stationary with respect to said frame and with respect to which said feeding means is laterally slidable, a plurality of laterally spaced projections on said stationary means, a sleeve fixedly secured to said feeding means and surrounding said stationary means, and a U-shaped locking member at each end of said sleeve engaging said projections and locking said sleeve to said stationary means at the desired spaced position of lateral adjustment.

8. In a manifolding machine adapted to be employed in association with a record printing machine having a plurality of laterally disposed and spaced type bar guides, means for feeding a plurality of superimposed sheets comprising a feeding finger adapted to engage a cooperating aperture in a plurality of superimposed sheets being fed, means adapted to allow adjustment of said feeding means laterally, laterally stationary means, a plurality of laterally spaced locking means thereon so disposed laterally that when said feeding means is locked thereto, said feeding finger will be in alignment with one of said type bar guides, and means allowing locking of said feeding means to any of said locking means only with said feeding finger in alignment with one of said type bar guides.

9. In a manifolding machine adapted to be employed in association with a record printing machine having a plurality of laterally disposed and spaced type bar guides, means for feeding a plurality of superimposed sheets comprising a feeding finger adapted to engage a cooperating aperture in a plurality of superimposed sheets being fed, laterally extending non-rotatable means with respect to which said feeding means is laterally slidable, a plurality of projections on said non-rotatable means spaced laterally at the same distance apart as said type bar guides and so laterally disposed that when said feeding means is locked relative thereto said feeding finger will be in alignment with one of said type bar guides, and means for so locking said feeding means to said projections and for thereby locking said feeding finger in alignment with one of said type bar guides.

10. In a manifolding machine adapted to be employed in association with a record printing machine having a plurality of laterally disposed and spaced type bar guides, means for feeding a plurality of superimposed sheets comprising a feeding finger adapted to engage a cooperating aperture in a plurality of superimposed sheets being fed, laterally extending stationary means non-rotatably fixed to the frame of the manifolding machine and with respect to which

said feeding means is laterally slidable, a plurality of independent projections on said stationary means spaced laterally at the same distance apart as said type bar guides and so laterally disposed that when said feeding means is locked relative to any one of said projections, said feeding finger will be in alignment with one of said type bar guides, a sleeve surrounding said stationary means and fixedly secured to said feeding means, and a locking member at each end of said sleeve engaging one of said projections for so locking said feeding means.

11. In a manifolding machine, a supporting frame having side frame members and lateral means disposed therebetween, a carriage laterally slidably adjustably mounted on said lateral means, means for locking said carriage in any one of a plurality of predetermined laterally spaced positions of lateral adjustment, feeding means adjustably mounted on said carriage comprising two sprockets one of which is a drive sprocket and the other of which is a driven sprocket and a feeding chain carried thereby having extending spaced fingers and adapted to present said fingers in engagement with cooperating longitudinally spaced apertures in a plurality of superimposed sheets being fed thereby, and yielding means interposed between said carriage and said driven sprocket for continuously urging said sprocket away from said driving sprocket and thereby maintaining said chain taut, said yielding means being mounted on said carriage and slidable therewith.

12. In a manifolding machine, a supporting frame having side frame members and lateral means disposed therebetween, a carriage laterally slidably adjustably mounted on said lateral means, means for locking said carriage in any one of a plurality of predetermined laterally spaced positions of lateral adjustment, feeding means mounted on said carriage comprising two sprockets, one of which is a drive sprocket and the other of which is a driven sprocket and a feeding chain carried thereby having extending spaced fingers and adapted to present said fingers in engagement with cooperating longitudinally spaced apertures in a plurality of superimposed sheets being fed thereby, and a fixed rod passing through said driven sprocket and carrying freely rotatable drums of larger diameter than said sprocket which are adapted to guide said sheets and strip them from said feeding fingers, said rod and drums being mounted on said carriage and slidable therewith.

13. In a manifolding machine, a supporting frame having side frame members and lateral means disposed therebetween, a carriage laterally slidably adjustably mounted on said lateral means, means for locking said carriage in any one of a plurality of predetermined laterally spaced positions of lateral adjustment, feeding means mounted on said carriage comprising two sprockets, one of which is a drive sprocket and the other of which is a driven sprocket and a feeding chain carried thereby having extending spaced fingers and adapted to present said fingers in engagement with cooperating longitudinally spaced apertures in a plurality of superimposed sheets being fed thereby, a fixed rod passing through said driven sprocket and carrying freely rotatable drums of larger diameter than said sprocket which are adapted to guide said sheets and strip them from said feeding fingers, said rod and drums being mounted on said carriage and slidable therewith, said driven

sprocket being yieldingly mounted with respect to said driving sprocket.

14. In a manifolding machine, a supporting frame having side frame members and lateral means disposed therebetween, a carriage laterally slidably adjustably mounted on said lateral means, means for locking said carriage in any one of a plurality of predetermined laterally spaced positions of lateral adjustment, feeding means mounted on said carriage comprising two sprockets, one of which is a drive sprocket and the other of which is a driven sprocket and a feeding chain carried thereby having extending spaced fingers and adapted to present said fingers in engagement with cooperating longitudinally spaced apertures in a plurality of superimposed sheets being fed thereby, a fixed rod passing through said driven sprocket and carrying freely rotatable drums of larger diameter than said sprocket which are adapted to guide said sheets and strip them from said feeding fingers, said rod and drums being mounted on said carriage and slidably therewith, and yielding means interposed between said carriage and said driven sprocket and slidable with said carriage for pushing said sprocket away from said driving sprocket and thereby maintaining said chain taut.

15. In a manifolding machine, a supporting frame comprising side frame members and lateral means therebetween, a carriage laterally adjustably slidable on said lateral means, means for locking said carriage in any one of a plurality of predetermined laterally spaced positions of lateral adjustment, feeding means mounted on said carriage and comprising a feed-

ing chain having spaced feeding fingers adapted to engage cooperating longitudinally spaced apertures in a plurality of superimposed sheets being fed thereby, a fixed rod mounted on said carriage and carrying freely rotatable drums adapted to guide said sheets and strip them from said fingers, bail means pivotally supported about said rod for holding said sheets in engagement with said fingers, and means for locking said bail means in a position in which it holds said sheets in engagement with said fingers.

16. In a manifolding machine, a supporting frame comprising side frame members and lateral means therebetween, a carriage laterally adjustably slidable on said lateral means, means for locking said carriage in any one of a plurality of predetermined laterally spaced positions of lateral adjustment, feeding means mounted on said carriage and comprising a feeding chain having spaced feeding fingers adapted to engage cooperating longitudinally spaced apertures in a plurality of superimposed sheets being fed thereby, a fixed rod mounted on said carriage and carrying freely rotatable drums adapted to guide said sheets and strip them from said fingers, bail means pivotally supported about said rod for holding said sheets in engagement with said fingers, means for locking said bail means either in a position in which it holds said sheets in engagement with said fingers or in a position where it enables threading of said sheets along said fingers and around said drums.
